UNITED STATES PATENT OFFICE.

CHARLES L. DEPOLLIER, OF NEW YORK, N. Y., ASSIGNOR TO DUBOIS WATCH CASE COMPANY, OF BROOKLYN, NEW YORK, A CORPORATION OF NEW YORK.

DESIGN FOR A WATCH-BRACELET.

47,376.

Specification for Design.

Patented May 25, 1915.

Application filed October 7, 1914. Serial No. 865,593. Term of patent 3½ years.

To all whom it may concern:

Be it known that I, CHARLES L. DEPOLLIER, a citizen of the United States, residing in New York city, in the county of Kings and State of New York, have invented a new, original, and ornamental Design for Watch-Bracelets, of which the following is a specification, reference being had to the accompanying drawing, forming a part thereof.

Figure 1, is a front elevation illustrating

my new design with the bracelet band shown in perspective, and Fig. 2, is a similar view showing the bracelet band broken away.

I claim:—

The ornamental design for a watch bracelet, as shown.

CHARLES L. DEPOLLIER.
